Primary Examiner — Susan Bennett Hattan(57) **CLAIM**

The ornamental design for a container with nozzle, as shown and described.

DESCRIPTION

FIG. 1 is an isometric view of a front, top, and left side of an ornamental design for a container with nozzle;

FIG. 2 is a front elevational view of the container with nozzle of FIG. 1;

FIG. 3 is a rear elevational view of the container with nozzle of FIG. 1;

FIG. 4 is a left side elevational view of the container with nozzle of FIG. 1;

FIG. 5 is a right side elevational view of the container with nozzle of FIG. 1;

FIG. 6 is a top plan view of the container with nozzle of FIG. 1; and,

FIG. 7 is a bottom plan view of the container with nozzle of FIG. 1.

The broken line showing in the figures is for the purpose of depicting environmental structure only and forms no part of the claimed design.
